[57] CLAIM

The ornamental design for a fuel dispenser housing, as shown and described.

DESCRIPTION

FIG. 1 is a perspective view of the fuel dispenser housing; FIG. 2 is a front elevational view thereof, the opposite side view being the same;

FIG. 3 is a side elevational view thereof, the opposite side view being the same;

FIG. 4 is a top plan view thereof; and,

FIG. 5 is a bottom plan view thereof.

It being understood that the broken lines in FIGS. 1 and 2 are for illustrative purposes only and form no part of the claimed design.
